UNITED STATES PATENT OFFICE.

SAMUEL B. BRILHART, OF NEW YORK, N. Y.

CAR TRUCK.

1,408,167.

Specification of Letters Patent. Patented Feb. 28, 1922.

Application filed August 18, 1920. Serial No. 404,393.

To all whom it may concern:

Be it known that I, SAMUEL B. BRILHART, a citizen of the United States, and a resident of the city of New York, borough of Manhattan, in the county and State of New York, have invented a new and Improved Car Truck, of which the following is a full, clear, and exact description.

This invention relates to railway rolling stock and especially to car trucks of the general type or character described and claimed in my co-pending application Serial No. 369,196, filed March 27, 1920.

Among the objects of the present invention is to improve or develop this type of car trucks having reference to ease and reliability of relative movement between the sectional car bodies and the supporting truck frames; the means for pivotally connecting the car bodies together for relative lateral movement; the means for preventing undesired lateral movement relatively between the car body connecting means and the center truck beneath the same, and the specific construction of the truck frame adjacent to the bearing boxes.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

Figure 1 is a plan view showing three interconnected truck sections and showing in dotted lines the approximate location of the two car sections supported thereon and jointed together.

Fig. 2 is a vertical sectional detail on the line 2—2 of Fig. 1.

Fig. 3 is a vertical transverse section of the same on the line 3—3.

Fig. 4 is a vertical section on the line 4—4 of Fig. 1.

Fig. 5 is a vertical transverse sectional detail of the same on the line 5—5.

Fig. 6 is a vertical transverse section approximately on the line 6—6 of Fig. 1.

Fig. 7 is a side elevation of a portion of a truck section as will be seen looking in the direction of the arrow 7 of Fig. 6. 55

Fig. 8 is a sectional detail on the line 8—8 of Fig. 7.

Fig. 9 is an enlarged vertical section corresponding approximately to the left end of Fig. 6, and indicating a slight variation in 60 spring supports.

Fig. 10 is a plan view of the bottom portion of the car section with the floor removed showing the car rollers and truck pivot connections, the same being adapted for a two 65 motor equipment.

Figs. 11 and 12 show variations in form and arrangement of car rollers in side elevation.

Fig. 13 is a diagrammatic plan view of a 70 modified form of centering means for the car body connections.

Fig. 14 is a vertical longitudinal section of the car body pivot means, the section being on a plane corresponding to the line 75 14—14 of Fig. 13.

Fig. 15 is a diagram indicating an arrangement of truck sections with interconnections between them, pertaining to a three section car. 80

Referring now more specifically to the drawings I show in Fig. 1 the location of two car sections A and B jointed together so that either may swing laterally with respect to the other as a result of either lateral curves 85 or vertical depressions in the track. The means for pivotally connecting the car sections includes primarily a pivot pin 20 fitted in a pair of lugs 21 (Fig. 14) extending horizontally from one of the car sections and having vertically aligned holes, and a lug 22 projecting from the other car section loosely into the space between the lugs 21. The lug 22 is provided with a large vertical opening 23 in which is mounted a bearing block 24 adapted to tilt laterally around a fore and aft axis 25 in the lug 22. The pin 20 projects through a vertical hole 26 in the bearing block 24 with sufficient looseness to provide for as much vertical tilting of one 90 car section as will be contemplated to ever take place with respect to the other due to rise and fall of the track. The lateral swaying of the car sections relatively is con-

80

85

90

95

100

siderable more than the vertical tilting, and this lateral swaying is amply provided for by the pivotal connection at 25 between the block 24 and its lug 22.

- 5 At the center of Figure 1 I indicate a center truck frame 27 having at its center a longitudinal slot 28 in and along which the pivot pin 20 is adapted to move as more fully set forth in said previous application, but 10 as indicated in Figs. 13 and 14 said center truck frame 27' is provided with a link 29 pivotally attached at 30 to one side of the frame and having at its other or free end a vertical eye 31. This link as shown in Fig. 15 15 lies between the lug 22 and the lower lug 21, and the pivot pin 20 passes through said eye. In this manner the pivot pin and parts connected thereby are held from lateral movement with respect to the frame 27', but 20 yet are permitted to move forward or rearward to compensate for such relative movement between the car connections and the truck frame beneath, as may be incident to the lateral turning of the jointed car around 25 lateral curves in the track.

The term truck as used herein will be understood as being applicable to the entire truck structure for supporting the pivotally connected car sections, either the two sections as in Fig. 1 or the three sections A, B and C as shown in Fig. 15. For each of the sections A and B remote from the pivotal connection thereof with the next adjacent section is an end truck section comprising 30 a frame 32 in which are journaled preferably two axles 33 with the usual track wheels.

The truck frame 32 includes a center bearing socket member 34 with which co-40 operates a downwardly projecting lug 35 carried by the bottom of the car section body or what may be termed the car frame. Located at any desired points laterally of the center bearing are co-operating bearings or anti-friction rollers, the truck rollers 45 being indicated at 36 and the car rollers being indicated at 37. In Figs. 6 and 9 the truck rollers 36 are shown mounted upon horizontal axes 38 transverse to the direction of movement of the car, and the car rollers 50 37 are journaled on axes 39 at an oblique angle to the axes 38. While the axes 39 may be horizontal it may be preferred in some instances to arrange them at an inclination as indicated in Fig. 11, and 55 whether the axes 38 and 39 are perpendicular to each other is dependent upon the type of truck and the specifications in any special equipment. In Fig. 1 I indicate the car rollers 37 arranged at oblique angles 60 at one end of the structure and at right angles to the truck rollers 36 at the other end of the structure. A practical arrangement for one of the trucks is for a single motor and the other is adapted for a two 65 motor equipment. Moreover as shown in

Figs. 10, 11 and 12, the bottom active surface of the car rollers 37 is arranged at an inclination whereby when the car sections thereby supported are shifted laterally there is a tendency for them to return to 70 normal position automatically by gravitation.

The truck rollers 36 are journaled in non-rotary boxes 40 resiliently supported for vertical movement in relation to the truck 75 frames 32. As indicated in Fig. 9 the cushions for the boxes 40 may consist of spiral or coil springs 41 interposed between the boxes 40 and the bottoms of frame casings 42, but in the better railway practice 80 elliptical springs, 41' are usually preferred to the coil springs because the elliptical springs tend to better resist lateral vibration or swaying of the truck frames, the elliptical springs being arranged transverse 85 to the planes of the wheels. As shown in Fig. 6 the truck rollers 36 and their shafts 38 may be journaled in arms 43 pivoted at 44 adjacent to the center bearing socket 34 whereby the lateral tilting of the car sections 90 may be provided for and the cushioning springs 41 or 41' may be made functional without disturbing the integrity of the truck sections. Since each pair of car and truck rollers are adapted for independent rolling 95 movement, either over the other, no friction can result from either the lateral tilting or lateral turning of the car sections with respect to the truck sections. These rollers are preferably roughened on their surfaces 100 to compel a rolling instead of a sliding action between them.

As in my previous application, the several truck sections have lever and link connections so as to compel proper alignment of 105 the several sections irrespective of lateral curves in the track. A brief reference, therefore, in this application to these features should suffice. Pivoted to the bottom of each car section A or B at 45 is 110 a lever 46. From the inner end of each lever 46 extends a link 47 whose remote end is connected at 48 to the side of the end truck frame. To the outer end of each lever 46 is pivoted a link 49 which extends 115 parallel to the track and is connected at 50 to the side of the center truck frame 27. In the two car section equipment the points of connection 50 for the two links 49 are on opposite sides of the same center truck 120 frame. Where more than two car sections are used the links 49' are jointed, the longer joints thereof extending parallel to the center car section C and are pivoted at both ends at 50' to the sides of the frames of 125 the center trucks 27' indicated in diagram as each comprising a single axle. The center truck frames will therefore always be maintained in parallelism.

Referring to Figs. 1, 2 and 4 the pairs of 130

car and truck rollers for the center truck frame are shown arranged differently in the front and rear portions of the same. In Fig. 2 the car rollers 37^a are mounted in arms 51 hung on horizontal pivots 52 on the bottom of the car section A, while the opposite ends of these arms are resiliently connected to the bottom of the car section by means of coil springs 53. Lateral movement of the arms with respect to the car body is prevented by vertical brackets 54. The truck rollers 36^b co-operating with the rollers 37^a arranged transverse to the direction of movement of the car may be supported upon the center frame 27 by any suitable means. The rollers 37^b for the adjacent end of the car section B may be journaled in fixed or any other suitable bearings and co-operate with truck rollers 36^b shown as journaled in arms 55 pivoted at one end on horizontal pivots 56 to the center frame 27 and resiliently supported at their other ends by springs 57 supported upon the frame. Lateral movement of the arms 55 is prevented by brackets 58.

The end truck section frame 32 is peculiarly constructed with respect to the tie bar 59 and means for securing the same in its position spanning the open end of the U-shaped yoke 60 in which the bearing box 61 is located. The frame 32 is provided with vertical tapered holes 62 in which are fitted correspondingly tapered bolts 63 which pass through the ends of the tie bar 59. To prevent the shearing of the bolts as a result of fore and aft vibration or strain that would tend to cause relative movement between the frame and the tie bar longitudinally of the latter, these two parts are provided with registering grooves 64 and 65 respectively in which is fitted a transverse key 66. This key is held from displacement by upturned ends. With the attachment of the nuts 63' to the bolts, as indicated in Fig. 8, the connection is rigid and secure, and consequently any tendency of the weight of the structure to spring or spread the yoke 60 will be effectually resisted.

50 I claim:

1. In a car truck, a truck frame, anti-friction rollers journaled on said frame, a car body positioned above said truck frame, anti-friction rollers carried by the car body and having rolling contact with the anti-friction rollers journaled on said frame, each of the rollers carried by the car body being journaled in an arm arranged diagonally to the car body, means to pivot one end of the arm to the car body, and resilient means between the other end of the arm and the bottom of the car body.

2. In a car truck, a truck frame, anti-friction rollers journaled on said frame, a car body arranged above said frame, an

arm pivotally mounted on said car body and extending diagonally in respect to the car body, anti-friction rollers carried by each of said arms, the axis of the rollers carried by the arms coinciding with the axis of the arms, and resilient means arranged between the bottom of the car body and the free ends of said arms.

3. In a truck, a truck frame adapted to support a car body, anti-friction rollers journaled on said frame, an arm pivotally mounted on said car body adjacent each of said anti-friction rollers, said arms extending diagonally to the car body, a roller carried by each of said arms having rolling contact with said anti-friction rollers, a plurality of spaced guiding brackets secured to the car body and extending downwardly therefrom on opposite sides of said arms to prevent relative lateral movement between the arms and the car body.

4. In a car truck, a truck frame adapted to support a car body, means for mounting rollers on the under surface of said car body so that their axes will be diagonal in respect to the car body, an anti-friction roller journaled on said truck frame for each of the rollers carried by the car body, said anti-friction rollers having rolling contact with the other rollers, an arm for each of the anti-friction rollers carried by the truck, each of said arms being pivoted to the truck and resilient cushioning means interposed between said arms and the truck frame.

5. In a car truck, a truck frame, anti-friction rollers journaled on said frame, a car body above the frame, anti-friction rollers carried by said car body and having rolling contact with the rollers on said frame, the car rollers and the truck rollers being arranged at an angle to each other, an arm pivotally mounted on said truck frame for each of the truck rollers, said arms extending transversely of the truck frame, and means for journailling the truck rollers on said arm so that the axes of the truck rollers coincides substantially with the axes of said arms.

6. In a car truck, a truck frame, anti-friction rollers journaled on said frame, a car body above the frame, anti-friction rollers carried by the car body and having rolling contact with the frame rollers, the car rollers and truck rollers being arranged at an angle to each other, an arm pivotally mounted on the frame for supporting each of said truck rollers, resilient means for supporting the outer ends of each of said arms, and guiding brackets for each of said arms fixed to the truck frame to prevent relative lateral movement between the truck frame and the arms.

7. In a railway truck the combination with a truck frame having a gap and a tie bar spanning said gap, of means securing

the bar to the truck frame including a key fitting transversely of the bar into registering slots of the bar and frame, and means acting between the bar and frame to hold the parts in position.

8. In a railway truck, the combination with a truck frame having a gap and a tie bar spanning said gap, of means securing the bar to the truck frame including a key fitted transversely of the bar into registering slots of the bar and frame, means acting between the bar and frame to hold the parts in position, said last mentioned means including a tapering bolt, the shearing of which is prevented by said key.

9. In a railway truck, the combination with a truck frame having a gap and a tie bar spanning said gap, of means securing the bar to the truck frame including a key fitting transversely of the bar into registering slots of the bar and frame, means acting between the bar and frame to hold the parts in position, said means including a tapering bolt provided with upturned ends to prevent the movement thereof laterally with respect

to the frame, the shearing of said bolt being prevented by said key.

10. In a coupling for the sections of a jointed car, the combination of a pair of vertically spaced lugs connected to one section, a single lug connected to the other section projecting between the spaced lugs, a coupling pin extending downward through all of the lugs, and means to prevent lateral shifting, said means including a link lying between said single lug and one of the lugs of the pair through which the pin projects.

11. In a center truck structure for jointed railway cars, the combination with a two car section and means connecting them together, of a truck frame beneath the connected portions of the car sections, and means to prevent lateral shifting of the car sections in respect to the frame, said means comprising a link, one end of which is pivoted to the side of the frame and the other end of which is pivoted to the coupling pin beneath the car sections.

SAMUEL B. BRILHART.
